UNITED STATES PATENT OFFICE.

EDGAR HAYSLETT, OF SOUTH BEND, INDIANA.

SPRING ROLLER.

Application filed August 15, 1921. Serial No. 492,411.

To all whom it may concern:

Be it known that I, EDGAR HAYSLETT, a citizen of the United States, residing in the city of South Bend, county of St. Joseph, Indiana, have invented certain new and useful Improvements in Spring Rollers, of which the following is a specification.

This invention relates to shade rollers, and especially to ratchet and spring devices therefor.

An object of my invention is to provide a novel and improved spring and ratchet device for a shade roller which may be applied to the end of a solid wood roller, or the like.

Another object of the invention is the provision of novel ball ratchet means for a shade roller. A third object of the invention is the provision of improved means for anchoring the inner and outer ends of the spring member. Still another object of the invention is the provision of improved means for inserting and retaining the ratchet balls of the ratchet mechanism. Other objects of the invention are mentioned and described herein.

The preferred embodiment of my invention is illustrated in the accompanying drawing in which Figure 1 is an elevation 30 of a shade roller to which my invention is applied; Fig. 2 is a section taken on the line 2—2 of Fig. 1; Fig. 3 is a section taken on the line 3—3 of Fig. 2; Fig. 4 is a view showing the ratchet cage cap; Fig. 5 is a view showing the roller ratchet shaft; Fig. 6 is a side elevation of a modified form of the locking plate for the ratchet mechanism; and Fig. 7 is a section taken on the line 7—7 of Fig. 2.

Similar numerals of reference indicate like members throughout the several views on the drawing.

Referring to the accompanying drawing in detail, the numeral 1 indicates a cylindrical cup-like spring casing member, preferably formed of ductile metal, which is provided with the hollow cylindrical roller socket portion 2 adapted to carry the shade roller end 3 therein, which socket portion 50 is reduced in diameter for that purpose. The casing 1 may be provided with a cup-like head 4 the flange whereof sleeves the former, said head being centrally apertured at 5, for the purpose hereinafter described.

The general structure of the spring casting contemplates and effects a spring cham-

ber 6 and a ratchet chamber 7, the latter being adapted to contain the ratchet cage and mechanism hereinafter described. Substantially, the ratchet cage comprises the 60 disk 8, disposed adjacent the end of the roller 3, the annular locking plate 9, and the cupped head member 10, the latter of which may have an annular flange on its outer periphery and within which the locking 65 plate 9 is arranged. The ratchet cage described is rigidly fixed within the casing socket 2, as a unit, and rotates therewith.

Numerals 11, 12 and 13 indicate apertures formed centrally of the members 8, 9 and 10, respectively, and axially of each other and of the casing head aperture 5. The locking plate 9 may be provided with a plurality of ball chambers 14, 14 disposed on opposite sides of the central aperture 12 75 and in communication therewith, each of said chambers having a lateral ball chamber or recess 15 formed intermediate the radial extremities of the chamber 14 and in communication with the bore 12, said lateral 80 ball chambers being adapted to serve as locking chambers, as hereinafter described.

Numeral 16 indicates a stub shaft having an annular reduced portion 17 loosely engaging in the central apertures 11, 12 and 13, respectively, of the members 8, 9 and 10, respectively, and a portion 18 disposed in the aperture 5 and the casing head 4, within which apertures said stub shaft gains its bearings. The shaft 16 is provided also with 90 a flattened end portion 19 adapted, as is well known, to engage in a bracket—not shown—to confine said shaft against rotation. The numeral 20 indicates a slit or incision formed longitudinally of and in the stub shaft 16 and terminating adjacent the shaft portion 18. Numeral 22 indicates a coil spring disposed within the casing chamber 6, the inner end whereof is bent for arrangement within the shaft slit 20, 100 for anchorage therein, and the outer end thereof is hooked at 23 and projected through the aperture 24 formed in the casing 1, said hook being overlaid by a bulged portion 25 of the flange of the casing head 4. 105

A locking ball 26 is movably disposed in each of the chambers 14, each of which balls has a range of movement from the outer extremity of said chamber to and within the locking chamber 15, in which latter position the ball projects slightly into the slit 20 of the stub shaft to effect the locked

2
relation between the ratchet cage and said shaft. See Fig. 3.

It is important in this invention to be able to introduce, or assemble, the balls 26 in the chambers 14, subsequent to inserting the shaft 16 in the bearing apertures 11, 12 and 13, and this is accomplished by punching or stamping the apertures 27, 27 in the head member 10, introducing the balls 26 into the chambers 14, and thereafter folding or pressing the ragged edges of the hole 27 back flush with the face of the head 10, thereby closing said apertures, as indicated by numeral 27^a in Fig. 4 of the drawing.

15 In the modification shown in Fig. 6 of the drawing the ball chamber 14 is provided with a relatively straight wall 28 which is disposed somewhat tangentially of the annular locking plate 9, which structure has 20 been found to give effective and very satisfactory results.

Obviously, when the roller is rotated, the stub shaft 16 is held against rotation in the bracket of well known construction, and the 25 spring 22 will be wound within the casing, whereupon one of the balls 26 will roll into a recess 15 of the locking plate 9, thereby disposing a portion of the ball within the slit 20 of the portion 17 of said stub shaft. 30 The effect of this movement of the detent ball 26 is that the coil spring 22 will be held in tension and the roller confined against retrograde rotation. In that respect the effect is similar to that produced by the 35 well known pivoted pawls or dogs employed in the shade rollers now in common use.

I claim:

1. In a device of the character described, a casing provided with a reduced roller 40 socket portion; a ratchet cage rigidly arranged within said casing socket portion, said cage comprising a centrally apertured locking plate provided with a plurality of chambers adapted to contain movable detent members, and a pair of cheek plates disposed on opposite sides of said locking plate, said cheek plates being centrally apertured axially of the central aperture in said locking plate; a stub shaft arranged in said 45 locking cage central aperture; and a coil spring within said casing and having its inner and outer ends connected, respectively, with said stub shaft and said casing.
- 50 2. A device of the character described

comprising a casing having a tubular extension for the reception of one end of a shade roller, said casing having a centrally disposed aperture in the end thereof; radially extending and oppositely disposed recesses formed in the side walls of said casing central aperture, said recesses being provided with lateral closure means, the side walls of said casing central opening being formed with oppositely disposed and off-set recesses inwardly of the first named recesses; a spring coiled within said casing and having one end thereof anchored within the casing; a stub shaft disposed in the casing central opening and having a longitudinal slit therein, the inner end of said spring 65 being anchored within said slit, that portion of said stub shaft which is arranged within said central opening having opposite recesses arranged for cooperation with the last named recesses for the reception of 70 detent members normally located within the first named recesses and movable therein.

3. A spring winding device for a shade roller comprising a casing provided with a tubular extension adapted to receive one 80 end of a shade roller; a casing head provided with a centrally arranged aperture; a locking plate rigidly arranged within said casing extension portion and movable therewith, said locking plate being centrally 85 apertured and provided with a pair of radially arranged and oppositely disposed ball chambers which open into said central aperture, the side walls of said central aperture being formed with oppositely disposed 90 and off-set ball recesses at the inner extremity of said ball chambers; a spring coiled within said casing and having its outer end anchored in the casing wall; a 95 stub shaft disposed in said casing head and locking plate central apertures, said shaft having a longitudinal slit therein in which the inner end of said spring is anchored; and said stub shaft having opposed recesses 100 adapted to cooperate with said last named recesses in said locking plate for the reception of detent balls normally located and movable within the first named recesses.

In testimony whereof I have hereunto affixed my signature this 11th day of August, 1921.

EDGAR HAYSLETT.
